UNITED STATES PATENT OFFICE.

JOHN L. SCHICK, OF CONNELLSVILLE, PENNSYLVANIA.

METHOD AND APPARATUS FOR MINING COAL.

Application filed July 11, 1921. Serial No. 483,763.

This invention is for an improved method of and apparatus for mining coal, and relates particularly to an improved automatic conveying system for transporting the coal in certain parts of the mine.

In the system of mining coal known in the art as the "room and pillar" system, a main entry is first dug into a seam of coal. Branching out from the entry at points about five or six hundred feet apart, are headings which are at right angles to the entry. Branching out from the headings at right angles thereto and parallel to the main entry are rooms. These rooms extend in only one direction, and are dug to a depth which leaves only a relatively thin wall of coal between the end of the rooms and the next heading. The rooms are usually about twenty feet wide and about five hundred feet deep, and are fifty to sixty feet apart. Each room is connected with the next adjacent rooms by passages which are parallel with the heading. The headings may be several hundred feet long, and therefore a large number of rooms may branch off from a single heading. Some of the rooms branching out from a heading will be extended almost to their limit, while others will just be started.

Tracks are laid in the main entry and in the headings for mine cars. The mine cars are hauled to and from the entrance to the rooms by mine locomotives, or by other suitable means. Tracks are also laid in the rooms as the rooms advance in length, the track being single. From the entrance to the rooms, the cars are pushed into the rooms, one or two at a time by the miners. The distance they have to walk pushing a single car increases as the depth or length of the room increases. Where a loading machine is used in the rooms, considerable time is lost in bringing up an empty car, loading it, removing the full car, and getting the next car into position.

In working the mine, a cutting machine goes through the rooms at night, making a cut to a depth of about six feet. After making a cut in one room, it is propelled to the next one. The cutting machine, if it does not "pull" the coal down, is followed by miners who blast or "shoot" the coal down, this also generally being done at night. The following day the loose coal is loaded, either by hand or by loading machines. The work of the loading machines is impeded

by the length of time required in getting cars to and from it, and therefore much of the advantage of such machines is lost.

When the rooms have been dug to the limit of their length, and the cross passages parallel with the headings are cut, these being cut progressively as the room lengthens, much of the coal will have been taken out, but there will still remain the blocks between parallel rooms and passages. As the rooms are dug, the posts and supporting structures are put in. The coal in the blocks is next removed by digging out the blocks furthest from the heading, pulling the posts and allowing the roof to fall. A retreat is thus gradually effected, and substantially all of the coal is removed.

The primary object of the present invention is to provide an automatic conveyor formed of sections, which may be used to convey the coal from the loading machine or point of loading to the headings, the conveyors being extended as the length of the room increases and shortened as the retreat is effected, and which conveyors may also preferably be arranged to extend around corners.

A further important object of my invention is to provide a special loader, particularly adapted for use in connection with the automatic conveyor to eliminate one dumping of the coal which is necessary when other loaders are used.

A still further object is to provide a combined conveyor carrying structure and mine supporting structure to eliminate some of the timber which is otherwise necessary, and render the mine more safe.

These and other objects are attained by my invention which is illustrated in the accompanying drawings, in which:

Fig. 1 represents a plan view of a portion of a mine, with my invention installed therein;

Fig. 2 represents a plan view of a single installation for one room;

Fig. 3 is a cross section on a slightly larger scale on line III-III of Fig. 2;

Fig. 4 is a side elevation of the apparatus shown in Fig. 2;

Fig. 5 is a plan view of a cable clamp or appliance used on the conveyor;

Fig. 6 is a transverse vertical section therethrough;

Fig. 7 is a perspective view showing a conveyor bucket trolley rail and joint;

Fig. 8 is a side view on a large scale of my improved form of loader;

Fig. 9 is a plan view thereof;

Fig. 10 is a vertical transverse section 5 through the loader;

Fig. 11 is a plan view of a special form of trolley track section for transferring buckets from the conveyor trolley track to a track above the loader;

10 Fig. 12 is a side elevation thereof;

Fig. 13 is a section on line XIII—XIII of Fig. 11.

Referring to Fig. 1 of the drawings which shows a plan view of a portion of a mine, 15 A is a heading which leads to an entry (not shown). B', B² and B³ represent three different rooms, of which there are a large number. The room B³ has been shown as being less far advanced than the other two 20 rooms. C indicates the parallel cross passages connecting the rooms, and D are solid blocks of coal which are not removed until the rooms have been extended to their limit. Extending from the heading longitudinally 25 of each room are sectional conveyors E. F indicates mine cars on tracks in the heading, and G is a loader at the front or loading terminal of the conveyor.

30 The conveyors E are of the traveling bucket type, it having heretofore been proposed to use sectional belt conveyors in other systems of mining than the room and pillar system. Belt conveyors are disadvantageous because of their great expense and 35 up-keep cost, and because of the difficulty in forming such a conveyor of detachable sections. They are furthermore disadvantageous because of the enormous increase in weight, with an increase in length, especially 40 when loaded.

The construction of the conveyors E are best shown in Figs. 2 to 7 inclusive. A discharging terminal section is provided at the mouth of the room. It comprises vertical posts 5 having screw jacks 6 at the base thereof and having caps 7 at their tops. There are preferably two such posts in the discharging terminal section, and they are connected by suitable framework at 8. Each 45 of the posts carries transverse cross arms 9. At the sides of the unloading terminal are parallel rail sections 10 supported on the arms 9, and they are connected at one end by a curved track section 11. Journalled in the framework connecting the two posts, is a vertical shaft 12 driven in any suitable way, such as by worm gearing, as 50 shown, by a motor 13. The upper end of the shaft 12 carries a large sprocket or sheave wheel 14, the diameter of which is somewhat less than the distance between the side track sections 10. The wheel is also spaced some distance back from the curved rail 11.

65 The loading terminal section of the con-

veyor is very similar to the discharge section. It is formed of two posts 5' similar to posts 5. The posts 5' are connected by frame members 15, and a sheave or sprocket wheel 16 is supported therein, the sprocket 70 wheel, however, not being driven by a motor, as the wheel 14 is. Parallel side track sections 17 are carried by cross trees on the post, and correspond to track sections 10. A curved track connecting the ends 75 may be provided where a usual form of coal loader is employed, but I prefer that this be omitted when my special loader, hereinafter described, is employed. Such a curved end section is indicated at 17^a in dotted lines in 80 Fig. 2.

Interposed between the loading and unloading sections are as many additional posts 5^a as are necessary, these posts also preferably corresponding to posts 5 and 85 having cross trees 18 thereon. One of the posts is shown in detail in Fig. 3. These posts are preferably placed apart at six foot intervals. They are designed to support parallel trolley track sections 19. The 90 track sections are preferably formed of angle iron of sufficient strength, and they are adapted to be connected with each other or with the similar tracks 10 and 17 on the terminals in any suitable way, such as shown 95 in Fig. 7, wherein an angle shaped connecting section 20 is used. The track sections 19 are preferably about six feet in length, but this can be varied to suit different conditions. They may be curved 100 where necessary, as indicated in Fig. 1.

Passing over the sheaves or sprockets 14 and 16 is an endless sectional cable 22. The cable is formed of sections preferably slightly more than twelve feet long, and the 105 ends of the sections are connected by any suitable clamps 23, such as that shown in Figs. 5 and 6. These clamps are in the form of a divided sphere having rope receiving recesses therein and held together by bolts. 110

Movable on the trolley tracks are trolleys 24 from which depend hangers 25 having hooks 26 at their lower ends. Buckets 27 are suspended from these hangers by trunnions 28 which engage in the hooks 26. At 28 is 115 a spring catch or other suitable means for normally preventing the buckets from swinging. On each bucket is a projecting yoke or bifurcated plate 29. This is adapted to receive the cable 22, and the clamps 23 are 120 designed to move the buckets by contact with said plates 29.

Assuming that a curved track section 17^a is used, the operation and method of using my invention is as follows. After the room has been mined to a sufficient length, the discharge terminal and the loading terminal are secured in place by means of the combined posts and jack 5 and 5', the loading terminal being spaced only a short distance 130

back of the inner end of the room. Posts 5^a are set up, and the track sections 19 are joined until a continuous track is formed. The cable 22 is also connected up and placed around sheaves 14 and 16. The motor 13, turning shaft 12, revolves the wheel 14 and this transmits motion to the endless cable. The trucks 24 with buckets suspended therefrom are placed on the tracks, and the 10 clamps 23, contracting with members 29, move the buckets.

On the curved tracks 11 and 17^a the buckets are out of the path of travel of the cable, and hence can remain stationary. 15 Coal may be shoveled in the stationary buckets at the loading terminal by hand, or the buckets can be loaded by a loading machine. After being filled, the trucks or trolleys 24 are pushed around on to the 20 straight track sections 17, where the cable will move them down to the discharge end where the trolleys, on track 11, are out of engagement with the cable. There the buckets may be dumped into mine cars F. 25 Clamp members 23 can be secured to the cable 22 at other places than at the joining of the rope sections, in order to provide additional bucket engaging means.

After the loose coal is loaded, the cutting machine moves in to make a cut of about 30 six feet. This coal is pulled or shot down, and the loading terminal is disconnected from the last section of track 19 and the cable is disconnected at one joint. The whole terminal section is moved forward six feet, and a new post 5^a is set. Then additional track sections 19 are inserted at each side, connecting the terminal sections of track 17 with those sections of track already in place. 35 An additional section of cable 22 and another clamp 23 is added, and the operation of loading coal may be resumed. Thus, after each 40 cut, the conveyor may be quickly and easily extended.

The posts 5^a serve to assist in supporting the roof, eliminating some of the timbering which would otherwise be necessary. Sufficient buckets can be provided so that the 45 operation of loading can be carried on continuously until the loose coal in the room is all loaded. After loading of the loose coal, the miners can go to the next room, which is similarly provided with conveyors, while new timber is put in the next cut made, and shot down, and the conveyor extended. Thus, the various operations may be carried 50 on successively in different rooms. It is estimated that three cuts can be made in each room with my system in a working day, whereas it now requires three days for loading 55 the same amount of coal.

In order to eliminate the dumping of the coal from a loading machine into the buckets, and in order to facilitate loading 60 the coal in a system of this kind, I have de-

vised an improved loader G, which is preferably used in connection with the conveyor. When the loader G is used, the curved end section 17^a on the receiving or loading terminal is dispensed with.

The loader is shown in Figs. 8, 9 and 10. It comprises a body member 35 supported on a tractor or other propelling means 36. Rotatably supported on the body is a revolving table 37 pivoted at 38 and supported on 70 anti-friction means 39. On the body 35 is an annular rack 40, and at 41 is a pinion engaging the rack. The pinion is carried on a shaft 42 journaled in the table 37 and is driven through suitable gearing, such as 75 worm gearing 43, by motor 44. The table 37 may thus be revolved by the motor 44.

On the table 37 are supports 45 which carry a trolley track 50. A portion of the track is concentric with the center of rotation of the table 37, while a portion of it is 80 elongated, as clearly shown in Fig. 9.

Slidable in a guideway 51 on the table 37 is a ram or pusher bar 52 having rack teeth thereon at 53 adapted to be engaged by a 90 motor driven pinion 54 carried on shaft 55 journaled in suitable means on the table. Shaft 55 is driven in a suitable manner by a reversible motor 56, such as through worm 95 gearing 57.

Carried on the outer end 52' of the reciprocable bar 52 are two spaced apart side plates 58 and at 59 are journals for a transverse shaft 60. In each of the side plates 58 is a short vertical slot 58^a and a curved slot 100 58^b which has a vertically extending part 58^c parallel with the vertical slots 58^a.

Fixed to the shaft 60 is a toothed segment 61. Carried on the reciprocable bar is a reversible motor 62 for driving worm gear 63, 105 which meshes with the teeth on segment 61. Also keyed to shaft 60 is an arm 64 having its outer end pivoted at 65 to a block 66 slidably carried in a guideway 67 on a bucket receiving frame 68. The bucket receiving 110 frame 68 has sides 69 and 70, side 70 being in the form of a scoop and being co-extensive with the height of the conveyor buckets 27. The frame 68 has a stud 71 at each side thereof which is guided in slots 58^b—58^c. 115 Also carried on the bucket holding frame at 72' is a stud 72. The studs 72 engage in the vertical slots 58^a.

By driving the motor 62 when the parts are in the position shown in Fig. 8, the 120 frame 68 may be swung from a horizontal to a vertical position through the movement of arm 64, the axis of stud shafts 72 being the axis of rotation of the bucket frame. Upon further movement of arm 64, the bucket 125 frame 68 is raised vertically without swinging, studs 71 and 72 then being in substantially the same horizontal plane. By reason of the sliding pivoted connection provided between the frame 68 and the arm 64, the 130

arm 64 is enabled to move in an arc and effect the lifting movement of the frame 68 vertically.

In Figs. 11, 12 and 13, there is shown a track section by means of which the buckets with their trolleys may be transferred from the track section 17 of the loading terminal conveyor section to track 50 on the loader, and which is arranged to permit of the 10 loader being moved longitudinally of tracks 17, and enables the table 37 to be turned so that the bucket receiving frame 68 can be projected from either side on to the front of the body 35. The table is capable of being revolved through an arc of 180 degrees. The track 50, like tracks 17, are formed of 15 angle iron. The connecting track comprises parallel rail sections 75 connected by cross member 76. These rail sections 75 are in the 20 form of inverted channels or saddles which rest on the vertical parts of tracks 17. The track sections 75 have rounded ends 77 which are in the shape of saddles that engage the vertical flange of rail 50. The ends of 25 the rails are tapered or inclined, as indicated at 75' in Fig. 12.

From the foregoing, it may be seen that the trolleys 24 from which the buckets 27 are suspended, can be moved along one of 30 the tracks 17, onto one of the track sections 75, and thence on to the curved track 50 on the loader, and from the loader track 50, they can be moved over the other of rails 75 on to the other of the parallel rails 17. The 35 connecting tracks 75 allow the loader to move forwardly or rearwardly, and permit the track 50 to turn with the table 37.

In operation, the buckets are moved by hand on to the track 50 of the loader in the 40 manner just described, and positioned over the frame 68, the reciprocable frame or bar 52 then being in retracted position. After a bucket has been properly positioned, motor 62 is operated, swinging the frame 68 until 45 the side 70 is vertical. Then the frame 68 moves vertically as hereinbefore described. In lifting up, the bucket 27 is received in the frame 68 and also lifted, the trunnions 28 lifting out of hooks 26. After the trunnions 50 have been lifted entirely out of the hooks, the motor 56 is operated to move the bar 52 forwardly just a slight distance, so that the trunnions 28 on the bucket will clear the hooks 26. Then the frame 68 is lowered 55 again to the position shown in Fig. 8, and the bucket is retained therein. Motor 56 is then operated to drive the bar 52 forward, moving the bucket along the ground into the loose coal. The bucket scoops up the coal, 60 and when it is loaded, motor 62 is again operated to raise the frame 68 before the extended bar 52 is retracted. So swinging the bucket to a vertical position completes the loading of the bucket and turns it to 65 such position that the coal will not lose out.

Then bar 52 is retracted until the trunnions 28 on the bucket again contact with hooks 26 on the trolley.

The frame 68 can then be lowered, but the trunnions on the bucket will engage the 70 hooks and be suspended from the trolley. The bucket with the trolley may then be pushed around on to the track 17 on the conveyor, where the member 23 on rope 22 will engage it and move it to the discharging 75 terminal. At the same time, another bucket may be similarly moved around into position over the bucket receiving scoop and filled. It is contemplated that a sufficient number of trolleys and buckets be provided in each 80 room to enable the operation to be carried on without any delay by waiting for buckets.

By having the track 50 move with the 85 table 37, the buckets can be lowered into the frame 68 at any position or angle at which it may be turned, the elongated portion of the track always remaining over the bar 52.

The loader can be moved from one room to another, so that a single loader may be used for working several rooms, which can 90 be provided with my conveyor. Thus, after the loose coal has been loaded from one room, the loader may be moved to the next, while an additional conveyor section is added in the room where the coal has just 95 been loaded, and other coal may be pulled down.

Various changes and modifications may be made in the construction of the conveyor and the loader, and the loader can be used in connection with or separately from the conveyor. It may be noted that where a system of this kind is employed, the rooms may be dug much longer than heretofore because no 100 delay is encountered in bringing cars up through the rooms. The headings may consequently be placed further apart, and consequently there need be fewer of them.

What I claim is:

1. The combination with a conveyor having removable buckets, of a loading machine having means thereon for receiving the buckets.

2. The combination with a conveyor having movable buckets, of a loading machine having a bucket receiving scoop thereon, said scoop being arranged to receive the buckets from a track and to return them to position to be returned to the track.

3. The combination with a conveyor having trolley tracks thereon, trolleys on the track, buckets carried by the trolleys, of a loading machine comprising a body having tracks thereon, means for transferring the buckets from the conveyor tracks to the tracks on the loader and from the loader to the conveyor, and means on the loader for filling the buckets.

4. The combination with a conveyor having trolley tracks thereon, trolleys on the

track, buckets carried by the trolleys, of a loading machine comprising a body having tracks thereon, means for transferring buckets to and from the conveyor tracks and 5 loader supported tracks, and a reciprocable bucket receiving scoop on the loader adapted to receive the buckets from the tracks on the conveyor, fill them, and return them to the tracks.

10. 5. The combination with a conveyor having trolley tracks thereon, trolleys on the tracks, buckets removably suspended from the trolleys, of a loading machine having a body on which is a rotatable table, tracks 15 supported by the table and removable therewith, tracks having a slidable engagement with the tracks on the rotatable table, and connecting with the tracks on the conveyor, the arrangement being such that the trolleys 20 may be moved from and to the conveyor tracks and loader supported tracks while permitting the table to be rotated to different positions, a reciprocable bucket receiving scoop carried by the rotatable table and arranged to receive the buckets from the trolleys, fill them, and return them to the 25 trolleys.

6. The combination with a conveyor having trolley tracks thereon, trolleys on the tracks, buckets removably suspended from the trolleys, of a loading machine having a body on which is a rotatable table, tracks supported by the table and movable therewith, tracks having a slidable engagement 30 with the tracks on the rotatable table, and slidably connecting with the tracks on the conveyor, the arrangement being such that the trolleys may be moved from and to the conveyor tracks and loader supported tracks 35 while permitting the table to be rotated to different positions and permitting the loader 40 to be moved longitudinally relatively to the

conveyor, a reciprocable bucket receiving scoop carried by the rotatable table and arranged to receive the buckets from the trolleys, fill them, and return them to the 45 trolleys.

7. The combination with a conveyor having buckets thereon, of a loader having a reciprocable scoop thereon, means whereby the scoop may be turned in different directions, means for positioning the buckets in the conveyor over the scoop, said reciprocable scoop having a bucket receiving frame adapted to swing on a horizontal axis, the 50 arrangement enabling the bucket to be received therein, swung to a horizontal position, pushed into the material to be loaded by the reciprocation of the scoop, turned again to vertical position, and restored to 55 the track, means for operating the bucket receiving frame, and means for effecting the reciprocation of the scoop.

8. The combination with a conveyor having buckets thereon, of a loader having a reciprocable scoop thereon, means whereby the scoop may be turned in different directions, means for positioning the buckets on the conveyor over the scoop, said reciprocable means having a bucket receiving frame 60 adapted to swing on a horizontal axis, and being movable vertically, this arrangement enabling the bucket receiving frame to be swung to a vertical position, raised to receive a bucket, lowered, swung to a horizontal position, pushed into the material to be loaded by the reciprocation of the scoop to 65 fill the bucket, and enabling the frame to be again swung to vertical position, raised and returned to the track, means for operating the bucket receiving frame, and means for effecting its reciprocation.

In testimony whereof I affix my signature.
JOHN L. SCHICK.
